UNITED STATES PATENT OFFICE.

WILLIAM L. HANCOCK, OF DALLAS, TEXAS, ASSIGNOR TO THE MURRAY COMPANY, OF DALLAS, TEXAS, A CORPORATION OF TEXAS.

COTTON-HULL SEPARATOR.

Application filed January 28, 1924. Serial No. 639,005.

To all whom it may concern:

Be it known that I, WILLIAM L. HANCOCK, a citizen of the United States, residing at Dallas, in the county of Dallas and State of Texas, have invented certain new and useful Improvements in Cotton-Hull Separators, of which the following is a specification.

My invention is an improvement in machines for cleaning seed cotton from burrs and the like, and to open and to remove hulls. It may also be used effectively for removing grabots or locks of cotton from cotton-seed before the delinting process and to open, and rework lint cotton, if desired.

In the drawings:

Figure 1 is a cross-sectional elevation;

Figure 2 is a section on line 2—2 of Figure 1;

Figure 3 is a cross section, on an enlarged scale, showing the preferred arrangement of spikes on roller D, as on line 3—3 of Figure 2;

Figure 4 is a top plan view; and

Figures 5 and 6 are modifications, showing respectively air blast and brush removal of the lint cotton from the belt.

The casing X which encloses and supports the moving parts of my machine, is of rectangular shape in plan and its walls provide support for bearings for the various moving parts of the machine, as will be plain without further specification.

The main feature of my device is a belt or belts, A, carrying sharp short teeth or pins, *a*, with points inclined in the direction of movement of the belt, the operative face of the belt moving upward at a slight angle from the vertical. As shown in the drawings there are two of these belts, A, organized so that their operative faces diverge upwards, forming two walls of a V-shaped chamber. These belts are mounted upon rollers, A', A'', at their upper and lower ends, one of the rollers for each belt being suitably actuated to move the belt in the direction indicated by the arrows. A driving pulley A²¹, for example, may be employed to actuate a roller A² and that roller in turn to actuate through pulleys A²², the opposite roller A² and by pulleys A²³, A²⁴ at the opposite end, picker-rolls B and feed rollers C, while rollers A¹ actuated by the belt A in turn actuate the agitator D and the spiral conveyor E. Preferably an idler roller F, adjustable, is employed to maintain the desired tautness of

belt A. At the top of the casing X is a feed opening, X', through which the material is fed.

The operation is as follows: Cotton being fed through opening X' falls upon the spiked feed rollers, C, turning as indicated, by which the cotton is thrown against the upwardly moving reach of the belt A, the short, sharp teeth of which, projecting in the direction of upward movement of the belt, engage the lint. This throwing of the entering material by the feed rollers is facilitated by the rearward inclination of the spikes *c*', as indicated in the cross-section of Figure 1. As the material moves up, with the belt A, some of the burrs and hulls are detached and fall downward. Those that do not are struck by the spikes, *b*, on picker rolls B, revolving in the direction of the arrows, Figure 1, the points of the spikes being rearwardly inclined, and the burrs, hulls and other loose material are knocked clear of the lint engaged by the sharp teeth on the belt A. More or less of the lint will be knocked off by the rolls B, as some lint will cling to some of the burrs and hulls and some is loose, and this lint will either be thrown upon the belt again by the feed rolls C, or escaping these, will fall upon the belt, slanting inward, or will reach the agitator D which will throw the hulls and lint again on the belt till the hulls are freed. The clean hulls will then work downward to the converging lower ends of the belts A being thrown repeatedly against the belt A and will gradually fill the space directly beneath agitator D and by the action of that roller with its spiral flights of preferably rearwardly inclined spikes, *d*, will be urged to either end of the roller D and expelled from the machine through openings, *d*', in the side wall of the casing X. Some hulls and broken hulls, burrs and dirt and trash which get below the agitator D will pass downward to the screw conveyor E and so out of the machine. The lint which passes upward past picker rolls B is removed from the belt A by a suction air current, condensed upon the surface of the belt by a hood Y and passes by pipe Z to and through a fan, (not shown). The lint may, if desired, be removed by air blast apparatus or by brush. In Figure 5 I have shown an air blast installation. Pipe M confines pressure air, which is discharged through a slit against the teeth, *a*, on belt

A, in a direction to remove the lint and carry it to discharge pipe N. In Figure 6, the removal means is a brush, O, which strips the teeth, a, and discharges the lint into pipe, P.

5 I have shown and described my machine as of duplex construction the two belts and co-operating parts being opposed within a single case. This is the preferred form, but a useful single machine may be constructed, 10 by forming the casing with a wall along the section line 2-2 in Figure 1 and using but one belt and associated parts.

I claim:

1. In a cotton hull separator and opener, 15 a casing, having a feed opening and an exit opening; a toothed belt, supported for rotation on upper and lower rollers within the casing, the inner face of the belt moving upward to the exit opening at an angle from the vertical; a spiked roller opposite the feed opening, to receive the entering material and throw it against the upwardly moving belt; a spiked roller opposite the exit opening adjacent the belt to beat back hulls and the like 25 while permitting lint to pass on; means to remove the lint from the toothed belt, means to dispose of the separated hulls.

2. In a cotton hull separator and opener, 20 a casing having a feed opening in the top

and exit openings on opposite sides; opposed 30 toothed belts supported for rotation on upper and lower rollers within the casing, the opposed faces of each belt moving upward to an exit opening at an angle from the vertical and forming the sides of a V-shaped chamber; a pair of spiked rollers turning in opposite directions, to receive the entering material and throw it against the upwardly moving toothed belts; a spiked roller opposite each exit opening adjacent the belt to beat back hulls and the like, while permitting 35 lint to pass on; means to remove the lint from the toothed belt, means to dispose of the separated hulls.

3. As in claim 1, and having also beneath 40 the receiving roller, a hull chamber and a spirally spiked conveyor roller, to receive the separated hulls and eject them through openings in the wall of the casing.

4. As in claim 2, and having also beneath 45 the receiving rollers a hull chamber, the opposed faces of the belts being spaced apart to form a longitudinal slot through which the hulls may escape.

Signed at Dallas, Texas, this twenty sec- 50 ond day of January, 1924.

WILLIAM L. HANCOCK.
